(57) CLAIM

The ornamental design for a landscaping block, as shown and described.

DESCRIPTION

FIG. 1 is a top plan view of a landscaping block;

FIG. 2 is a first side elevational view thereof;

FIG. 3 is a second side elevational view thereof;

FIG. 4 is a third side elevational view thereof;

FIG. 5 is a fourth side elevational view thereof; and,

FIG. 6 is a bottom plan view thereof.

The broken lines in the figures depict portions of the landscaping block that form no part of the claimed design.

1 Claim, 1 Drawing Sheet
